COMBINED RADIO TRANSMITTER
AND RECEIVERDonald H. Mitchell, Chicago, Ill., assignor to
Motorola, Inc., a corporation of IllinoisOriginal application February 20, 1942, Serial No.
431,722. Divided and this application March
31, 1943, Serial No. 431,196

6 Claims. (Cl. 200—16)

1

The present invention relates generally to radio apparatus and in particular to a portable self-contained combination radio receiver and transmitter unit. This application is a division of co-pending application Serial No. 431,722, filed February 20, 1942.

The combination portable radio receiver and transmitter units now generally used are not entirely satisfactory because of their bulk and weight, and the inconveniences encountered in setting them up for operation. In most instances these prior art sets are not self-contained as a package unit and usually include an earphone unit or an antenna unit which are separately attachable to the body of the set by extension wires or the like. As a result these are not capable of operation immediately on reaching a new destination or while enroute to such destination, since some time must be used for assembling the earphone or the antenna units and for making various tuning and control adjustments. Further because of the bulk of the sets they are difficult to handle and generally too heavy to be manually supported while in operation. In fact many of them require special supporting means upon which the various parts of the set are relatively arranged in a manner to facilitate their use. The maneuverability and the flexibility of application of these sets to the various field demands required of sets of this type, such as in an army signal corps, police work and the like, is thus appreciably restricted. Even after the sets are assembled for operation considerable delay is usually involved in the transmission and reception of signals because of the time lost in changing from transmitting to receiving and vice versa. Also because of their relatively complicated structure, the component parts of the prior art sets are usually completely dismantled for servicing and replacement purposes. Another objection to these sets is that they are open to the atmosphere whereby their use on rainy days is generally impaired or restricted to places having suitable shelters therefor. Further these sets are generally unprotected against rough handling or dropping so that great care must be exercised at all times to prevent permanent injury thereto.

It is an object of this invention, therefore, to provide an improved radio apparatus.

Another object of this invention is to provide an improved combination radio receiver and transmitter unit.

It is a further object of the invention to provide improved switching apparatus for selectively intercoupling the electron discharge tubes of a com-

2

bined radio transmission and receiving system to provide either a signal receiving channel or a signal transmitting channel.

A feature of this invention is found in the provision of radio equipment capable of being completely enclosed within an elongated housing in which linearly movable contact means for longitudinally extending switch means within the housing is actuated by manual means on the outside of the housing movable substantially in a direction normal to the linear direction of movement of said contact means.

Further objects, features, and advantages of this invention will become apparent from the following description when taken in connection with the accompanying drawings in which:

Fig. 1 is a front perspective view of the radio unit of this invention as it appears when not in use;

Fig. 2 is a fragmentary sectional view showing the manually operated means for actuating the change-over switch;

Fig. 3 is a plan view of the chassis unit, the unit being shown in actual size;

Fig. 4 is a side elevational view of a transparent insulating member which forms a part of the switch means for changing the operation of the combination set of this invention from a receiver to a transmitter and vice versa; and

Fig. 5 is a plan detail view of the change-over switch means.

In practicing this invention there is provided a portable self-contained combination radio receiver and transmitter set which is compact and light in weight so as to be easily carried about or supported in one hand.

A single switch means is utilized to change the set over from operating as a receiver to a transmitter and vice versa. The switch means is assembled as a part of the chassis unit and is positioned entirely within the housing. A manually operated unit for actuating the change-over switch means projects outwardly from one side of the housing, and is arranged relative to the earphone and microphone units so as to be positioned below the one hand of the operator used in supporting the set in an operating position. It is necessary merely to press and release the change-over switch with such supporting hand to immediately change the set from a receiver to a transmitter and vice versa.

Referring to the drawings the combination radio receiver and transmitter set of this invention is illustrated in Fig. 1 as including an elongated housing 40 of substantially square cross

section over its entire length and open at the ends 41 and 42 thereof. In order to make the complete set as light as possible in weight it is contemplated that the housing 40 be composed of aluminum or like material. Projecting portions 60 and 65 are provided on the housing 40 for earphone and microphone units and a manual switch operating unit 207 is provided on the housing as will be more fully explained. A cap 261 is provided for covering the extending tip of an antenna 136 (Fig. 3). The cap 261 is attached to the housing by a chain or the like 263 and is adapted to be positioned on a threaded holding flange 262 when the set is being used.

The switch operating unit 207 operates a single control switch 192 (Figs. 2 and 5) assembled as a part of the chassis unit 52 which is used to completely change over the operation of the combination set from its function as a receiver to a transmitter and vice versa. The switch 192 extends longitudinally of the chassis unit 52 and to one side thereof across the tubes T1—T5, inclusive. The switch 192 includes a stationary insulating member or frame 193 of flat form and a movable insulating member 194 also of flat form and arranged for linear movement relative to the stationary member 193. Extending in linear alignment and arranged in a spaced relation longitudinally of the stationary member 193, are a plurality of groups of contacts 196 having engaging fingers 197 and 198 (Fig. 2). As illustrated for the switch contact 196a in Fig. 5, the stationary member 193 is formed with an aperture 199 for receiving therein the finger portion 197 of the switch contact 196a. The finger portion 198 of contact 196a is shown broken away. The finger portion 197 is thus retained substantially in the plane of the stationary member 193. It is to be understood, of course, that the above construction for the contact 196a is similar for all of the contacts 196.

The movable member 194 carries contacts 201 of substantially L-shape having a leg portion 202 (Fig. 2) extending through a corresponding slot 203 formed in the stationary member 193. The end 204 of the leg portion 202 is anchored in the movable member 194 so as to be retained in a fixed position thereon. A second leg portion 206 substantially normal to the leg portion 202 is projected laterally away from a corresponding slot 203 for positioning between the fingers 197 and 198 of corresponding contacts 196. By virtue of the finger 197 being substantially in the plane of the stationary member 193, the leg portions 206 are slidably supported for movement on the member 193 and through the finger portions 197 and 198 whereby to slidably support the movable member 194 on the stationary member 193. Contacts 201 include portions engaging contacts on both sides of the stationary member 193. It is seen, therefore, that on linear movement of the movable member 194 relative to the stationary member 193 the contacts 201 are moved relative to corresponding contacts 196 to control the energization of the circuits associated with the contacts 196. Contacts on the stationary member 193 not engaged by any contacts 201 on the slideable member 193 are indicated at 208. These contacts 208 are merely the lugs for other circuit connections.

The operation of the switch 192 is manually controlled by a manually operated unit 207 operatively supported on the housing 40 and to the outside thereof (Fig. 2). The unit 207 includes toggle or extensible means 208 comprising a pair

of members 209 and 211 of substantially arcuate shape which are pivotally connected together at their adjacent ends by axis means 212. The end 213 of the toggle member 211 is pivotally connected by axis means 214 with a bracket member 216 secured to the housing 40 by a screw or the like 217 so that the end 213 is in a fixed position relative to the housing 40. The end 218 of the toggle member 209 is pivotally connected by axis means 219 with a linearly movable member 221 which is slidably supported on the housing 40. The linear movement of the slideable member 221 is in the same direction as the linear movement of the movable member 194 of the switch 192, the member 221 having guiding rim portions 223 thereon for receiving a guiding member 224 secured by a screw 226 to the housing 40. On pressing the toggle means 208 toward the right, as viewed in Fig. 2, the pivotal connection 212 between the toggle members 209 and 211 is moved in an arcuate path which is substantially normal to the direction of linear movement of the slideable member 221 and hence to the direction of linear movement of the switch member 194. This movement of the toggle means 208 linearly moves the end 218 of the toggle member 209 to in turn move the slideable member 221 in a linear direction. The position of the parts of the manually operated unit 207 when the toggle means is in a depressed condition is shown in dotted lines in Fig. 2. The movement of the pivotal connection 212 is limited by a cushioned bumper 227 carried on the housing 40 and secured thereto by the screw 217.

The slideable member 221 has an extension 228 thereon which extends through an opening 230 formed in the housing 40. This extension 228 is in abutting engagement with a projection 229 secured to the movable switch member 194 and extending laterally therefrom through a slot 231 formed in the stationary switch member 193. On movement of the pivotal connection 212 to the right, as viewed in Fig. 2, the extension 228 on the slideable member 221 is moved downwardly to in turn engage the projection 229 for movement therewith to their positions shown in dotted lines in Fig. 2. This downward movement of the projection 229 in turn linearly moves the movable member 194 in one direction relative to the stationary member 193 and hence the contacts 201 relative to the contacts 196 to control the radio circuits.

On release of the toggle means 208 the toggle member 211 is initially moved by a spring member 232 out of a binding position with the toggle member 209. The continued movement of the toggle means 208 to its unoperated position is accomplished by a tension spring 233 (Fig. 5) connected at one end to the stationary member 193 and at its opposite end to the movable member 194, the spring being partially positioned within a slot 234 formed in the stationary member 193. This action of the spring member 233 linearly moves the member 194 in an opposite direction relative to the member 193, with the engagement of the projection 229 with the extension 228 on the slideable member 221 returning the toggle means 208 to an idle position. When the manually operated unit 207 is in the position indicated in full lines in Fig. 2, the set is connected for operation as a receiver. With the toggle unit 207 in the position indicated in dotted lines in Fig. 2 the set is operated as a transmitter. It is seen, therefore, that changing the operation of the set from a transmitter to a receiver is auto-

matically accomplished simply by releasing the operating unit 207 and that the set will operate as a receiver so long as the unit 207 is retained in a depressed position. The change over from receiving to transmitting and vice versa is accomplished in a minimum of time and without any delay for making adjustments between the receiving and transmitting operations.

The flat arrangement of the change-over switch means 192 longitudinally of the chassis unit 52 and across one side of the tubes T1—T5, inclusive, provides for the contacts 198 and 201 corresponding to an associated tube being substantially adjacent such tube without projecting any appreciable distance laterally from the chassis unit 52. By virtue of a tube and its associated contacts being adjacent each other only very short leads or connections are required for connecting the contacts of the switch 192 into the tube circuits so as to substantially reduce the circuit losses resulting from long connections. A transparent insulating member 239 (Fig. 4) is arranged in a superposed relation with the switch unit 192 and is secured at each end thereof to the radio chassis 52. The transparent insulating member 239 is adapted to have applied thereon suitable markings, indicated as 241 (Fig. 3), to facilitate the assembly and checking of the tube circuits.

The passage of any moisture into the housing 40 from about the manually operated unit 207 for the change-over switch 192 is prevented by a rubber hood 271 having a central portion pre-formed to a shape corresponding to the shape of the toggle means 207 when the same is in a rest position and a flat rim portion 272 for fitting against the housing 40 (Fig. 2). The rim portion 272 is clamped against the housing 40 by a clamping plate 273 having an aperture 274 therein for receiving the toggle means 207 and the central preformed portion of the gasket 271, the plate 273 being secured to the housing 40 by screws or the like 276.

From a consideration of Fig. 1, it is seen that the housing portions 60 and 65 project from a common side of the housing 40 while the manually operated unit 207 projects from a next adjacent side of the housing 40. The housing portions 60 and 65 are inclined toward each other and are relatively spaced to provide for their use in the manner of a telephone set as indicated in Fig. 1. In other words with the housing 40 supported in one hand of the operator the microphone unit 63 is positioned near the operator's mouth while the earphone unit 62 is positioned near one of his ears. In the commercial embodiment of the invention previously mentioned, the housing 40 is about a foot long and approximately three inches square with the weight of the entire unit being only about five pounds. The housing 40 is thus capable of being easily grasped in one hand of the operator and by virtue of the light weight of the complete set can be readily and simply supported in an operating position which is common for both receiving and transmitting. The operating unit 207 for the change-over switch 192 is arranged relative to the housing portions 60 and 65 so as to be positioned below the hand of the operator which is used in holding the set in its operating position. By merely opening and closing the hand, therefore, the unit 207 is operated to control the change-over switch 192. It is seen, therefore, that the supporting of the set in an operating position, and the manipulation of the operating unit 207 to change from receiving

to transmitting and vice versa is accomplished entirely by one hand of the operator, so that the other hand of the operator is left entirely free for taking notations or performing other miscellaneous duties.

From a consideration of the above description and drawings, therefore, it is seen that the invention provides a combination radio receiver and transmitter set which is of a very compact construction, light in weight, and which is completely self-contained as to the antenna, source of energy supply, and all of the necessary operating component parts. A single switch is utilized for changing the set from transmitting to receiving and vice versa. Because of this simplicity in construction, assembly, and operation of the set, it may be readily operated efficiently by an unskilled operator. It is to be noted also that the combination set is immediately operative on turning on of the energy supply switch so that communications may be carried on while the operator is enroute to a destination or after he has arrived at such destination.

Although the invention has been described with specific reference to a particular embodiment thereof, it is to be understood that it is not to be so limited, since changes in the parts and in their relative arrangement can be made therein which are within the full intended scope of this invention as defined by the appended claims.

I claim:

1. An electrical slide switch comprising, a flat longitudinally extending stationary insulating member, a second flat longitudinally extending insulating member linearly movable relative to said first insulating member, first group of contacts spaced longitudinally of said first insulating member, a second group of contacts on said second insulating member cooperating with said first contacts, said first insulating member having apertures therein corresponding to said second group of contacts but laterally spaced therefrom, each of said second group of contacts being inserted through a corresponding slot in said first insulating member and extended laterally away from such corresponding slot for engagement with a corresponding one of said first group of contacts, said other group of contacts slidably supporting said second insulating member on said first insulating member for movement relative thereto.

2. An electrical slide switch comprising a flat insulating member having a slot therein, a second flat insulating member, a first contact carried by said first insulating member in a position laterally displaced from said slot, and a second contact carried by said second insulating member and extending through said slot, said second contact being provided with a portion extending laterally away from said slot toward said first contact to hold said members in assembled relationship for relative movement therebetween and to engage said first contact during relative movement between said members.

3. Electrical switching apparatus comprising, stationary contact means, cooperating movable contact means, a linearly slidable member supporting said movable contact means for movement relative to said stationary contact means, actuating means for moving said slidable member including a normally collapsed toggle generally parallel to said members and having a first link operatively connected to said slidable member and a second link pivoted at one end

to said first link and at the other to a fixed point of said apparatus, said toggle being extensible to effect linear movement of said slidable member, and means for biasing said toggle from said extended position to said collapsed position.

4. Electrical switching apparatus comprising, stationary contact means, cooperating movable contact means, a linearly slidable member supporting said movable contact means for movement relative to said stationary contact means from a first position to a second position, biasing means tending to hold said member in said first position, said linearly slidable member having a projection thereon, actuating means having a portion adapted to engage said projection for moving said slidable member from said first position to said second position, said actuating means including a normally collapsed toggle generally parallel to said member, said toggle including a first link connected to said actuating portion and a second link pivoted at one end to first link and at the other end to a fixed point of said apparatus, said toggle being extensible to effect linear movement of said engaging portion to move said slidable member from said first position to said second position.

5. An electrical slide switch comprising a flat longitudinally extending insulating frame having a slot extending longitudinally therein and substantially the entire length thereof, a flat longitudinally extending insulating member linearly movable relative to said insulating frame and supported thereon, a plurality of groups of contacts carried by said insulating frame spaced along the length thereof and laterally displaced from said slot, and a plurality of contacts carried by said insulating member extending through said slot and having portions extending laterally away from said slot toward said contacts on said insulating frame to hold said frame and said member in assembled relationship for relative movement therebetween, each of said contacts on said insulating member being adapted to be associated with a particular group of contacts on said frame and being dimensioned to correspond to said particular group of contacts, said contacts being positioned on said frame and on said member so that said contacts on said insulating member selectively engage said contacts on said insulating frame during relative movement between said frame and said member.

6. An electrical slide switch for use with an electrical system to change the connections in a

plurality of circuits in said system comprising, a flat longitudinally extending insulating frame having a slot extending longitudinally therein and substantially the entire length thereof, a flat longitudinally extending insulating member linearly movable relative to said insulating frame and supported thereon, a plurality of groups of contacts carried by said insulating frame along the length thereof with adjacent groups spaced from each other and laterally displaced from said slot, and a plurality of bridging contacts carried by said insulating member extending through said slot and having portions extending laterally away from said slot toward said contacts on said insulating frame to hold said frame and said member in assembled relationship for relative movement therebetween, said bridging contacts being individually associated with said groups of contacts on said frame and each being dimensioned to correspond to the particular group of contacts with which it is associated, said bridging contacts being positioned with respect to said groups of contacts to selectively interconnect said contacts of said groups during relative movement between said frame and said member.
